DESIGN FOR A COMBINED MASK AND RESPIRATOR

Howard M. Dodge, Wabash, Ind., and Herman T. Kraft, Akron, Ohio, assignors to The General Tire & Rubber Company, Akron, Ohio, a corporation of Ohio

Application December 5, 1938, Serial No. 81,595
In France October 7, 1938

Term of patent 14 years

To all whom it may concern:

Be it known that we, Howard M. Dodge, a citizen of the United States, residing at Wabash, in the county of Wabash and State of Indiana, and Herman T. Kraft, a citizen of the United States, residing at Akron, in the county of Summit and State of Ohio, have invented a new, original, and ornamental Design for a Combined Mask and Respirator, of which the following is a specification, reference being had to the accompanying drawing forming a part thereof, in which:

The figure is a perspective view of a combined mask and respirator showing our new design.

The dominant features of our design reside in the portions shown in full lines and both sides of the device are substantially like the sides shown, being symmetric on each side of a vertical plane through the forehead, nasal and chin portions of the mask.

We claim:

The ornamental design for a combined mask and respirator, substantially as shown and described.

HOWARD M. DODGE.
HERMAN T. KRAFT.
